CLAIM

The ornamental design of a control pod for a communications headset, as illustrated and described.

DESCRIPTION

FIG. 1 is a front, top, left 3/4 perspective view of a control pod for a communications headset showing my ornamental design.

FIG. 2 is a rear, right, bottom 3/4 perspective view of the control pod for a communications headset.

FIG. 3 is a top elevational view of the control pod for a communications headset.

FIG. 4 is a bottom elevational view of the control pod for a communications headset.

FIG. 5 is a rear elevational view of the control pod for a communications headset.

FIG. 6 is a front elevational view of the control pod for a communications headset.

FIG. 7 is a left elevational view of the control pod for a communications headset; and,

FIG. 8 is a right elevational view of the control pod for a communications headset.

The dashed lines illustrate portions of the control pod for a communications headset that are not part of the claimed design.
